UNITED STATES PATENT OFFICE.

THOMAS P. ARSNEAU, OF PORTLAND, OREGON.

MUSIC-LEAF TURNER.

1,271,829.

Specification of Letters Patent.

Patented July 9, 1918.

Application filed July 8, 1915. Serial No. 38,787.

To all whom it may concern:

Be it known that I, THOMAS P. ARSNEAU, a citizen of the United States, and a resident of the city of Portland, county of Multnomah, State of Oregon, have invented a new and useful Improvement in Music-Leaf Turners, of which the following is a specification.

This invention relates to devices for mechanically turning the sheets of a piece of music, and is adapted for use in connection with any type of musical instrument which requires a stand for holding music.

One of the main objects of my invention, is to provide a device of this character, which may be operated by the depression of a foot treadle, and thereby relieve the operator from the necessity of using the hands in operating this device.

Another of the main objects of my invention, is to provide a device which will operate, not only to turn the leaves consecutively in one direction, but which will also operate to return the leaves so that the music may be repeated.

Another of the main objects of my invention, is to provide a mechanical music turner which will be simple in operation and construction, and positive in action.

I have so arranged my device that the leaves of the piece of music are firmly gripped by spring clips. These spring clips are mounted on the outer ends of lever arms, and I connect these lever arms by a series of bell-cranks and links to a foot treadle, successive depressions of which will operate so as to consecutively turn the sheets one at a time, in one direction and the further depression of the foot treadle will simultaneously return all parts to their normal positions, so that the music may be repeated if desired.

In the accompanying drawings, I have shown my invention used in connection with a substantial music rack of a type ordinarily used in orchestra pits. However, it is to be construed that the invention may be used in connection with any other type of music stand. In these drawings:

Figure 1 is a front elevation of a music stand showing my invention incorporated therewith.

Fig. 2 is a left side elevation of the same.

Fig. 3 is a development of the cylinder cam which permits the successful operation of the music turner; and Fig. 4 is a diagram-

matic plan view showing the mechanical connection between the leaf turning arm and the operating connections thereto.

A standard *a* is mounted on the base *b*, and is provided at its upper end with an inclined face plate *c*, which acts as a support for the music turning device. On the rear of the face *c*, are fixed the guide staples *d*. A bracket *e*, is provided with longitudinally extending arms *f*, which are adapted to be removably supported in the guide staples *d*. The bracket *e* is made with a lateral flange *g*, and an extending arm *h*. A pendant pivot post *i* is rigidly mounted in the flange *g*, and said post is provided with a collar *j*. A plurality of lever arms *k*, *k'* and *k''* are pivoted on the post *i* above the collar *j*, said lever arms bearing on their outer extremities spring clips *l*, which are adapted to grip the sheets of the piece of music.

A stop arm *m* limits the throw of the lever arms when the latter are rocked to the left, having reference to Fig. 1. Pivoted on the bracket arm *h* are the bell cranks *n*, *n'* and *n''*, and these bell cranks are respectively connected by links *o*, *o'* and *o''* to the corresponding arms *k*, *k'* and *k''*.

On the base *b* of the music stand mounted rotatably are bearing arms *b'* in which rotates a cylinder cam *p*. This cylinder cam has fixed on one end, a pinion *q*, meshing with and driven by a gear *r*, the latter being rotatably mounted on a shaft *r'* in a bearing *r''*. A ratchet gear *s* is also mounted on the shaft *r'*. A foot treadle *t* is loosely journaled on the shaft *r'*, adjacent the ratchet *s*. Said treadle is provided with a spring pawl *t'*, adapted to engage with the teeth of the ratchet *s*, so that when said treadle is depressed, the pawl and therewith the ratchet *s* and the gear *r* will be rotated in a clockwise direction, having reference to Fig. 2. This movement will cause a counter clockwise rotation of the cam cylinder *p*, and the gearing connections between the shaft *r'* and the cam cylinder *p* are so figured, that a single depression of the foot treadle *t*, will cause a quarter revolution of the cam cylinder *p*.

The foot treadle *t* is provided with a rear arm *t''* extending through a slot *t''* in the standard *a*, and a spring *t''* normally holds the treadle in the position shown in Fig. 2. A cross arm *v*, which is an integral part of the bearing arms *b'*, has pivoted thereon bell cranks *w*, *w'* and *w''*, which are con-

nected by links w , w' and w^2 to the bell cranks n , n' and n^2 respectively. The cam cylinder p is provided with the three cam grooves y , y' and y^2 as shown in Figs. 1 and 3. The bell cranks w , w' and w^2 are each provided on one arm with cam rolls (not shown) which travel in the grooves y , y' and y^2 , respectively. These grooves are so formed that in beginning a cycle of operation, the first depression of the foot treadle will cause the bell crank w and thus the bell crank n and the arm k to be thrown over, thereby turning the first sheet of the piece of music. The next depression of the bell crank t will rock the bell crank w' and therewith the bell crank n' and the arm k' so as to turn the second sheet of music. The third depression of the foot treadle will rock the bell crank w^2 , and therewith the bell crank n^2 and the arm k^2 , so as to turn the third sheet. The fourth depression of the foot treadle will cause all bell cranks w , w' and w^2 to be simultaneously returned to their initial positions, which action will cause all three arms k , k' and k^2 to be turned so that the continued operation of the foot treadle will cause this cycle of action to be repeated. In actual use, the music is placed in the position shown by the broken lines z . The center of the sheet is engaged by the pendant pivot post i , and the spring clips l hold the sheets in convenient position for use.

In these drawings, the device is shown as designed for use in turning three pages of music, but by increasing or decreasing the number of unit parts thereto, the device can be used for consecutively turning and simultaneously returning any number of sheets.

I claim:

1. In a music leaf turner, the combination of a pivot post, a plurality of leaf turning arms pivotally supported thereby, a rotatable cylinder provided on its periphery with a plurality of continuous cam elements, said cam elements having portions to operate the leaf turning arms in one direction and portions to operate the leaf turning arms in the opposite direction, the portions of the respective cam elements for operating the arms in the first mentioned direction being arranged one in advance of the other, connections between the cams and the leaf turning arms, and means for intermittently rotating the cylinder to cause the cam portions to first successively turn the leaf turning arms in one direction and subsequently return all said arms to normal position.

2. In a music leaf turner, the combination of a plurality of pivotally mounted leaf turning arms, a cylinder provided on its periphery with a plurality of continuous cam elements having portions disposed one in advance of the other and offset, and other cam portions on said continuous cam elements arranged in transverse alignment, connections between the cylinder and the leaf turning arms, and pedal operated means for intermittently rotating the cylinder.

3. In a music leaf turner, the combination of a pivot post, leaf turning arms pivotally supported thereby, pivotally mounted bell crank levers connected to the leaf turning arms, longitudinally movable rods pivoted to the bell crank levers, a cylinder having a plurality of continuous cam elements having portions disposed one in advance of the other and offset, and other cam portions on said continuous cam elements arranged in transverse alignment, bell crank levers between the cam portions and the lower ends of the longitudinal rods, and pedal operated means for intermittently rotating the cylinder to cause the cam portions in advance of the other and offset to successively turn the leaf turning arms in one direction, and the transverse aligned cam portion to subsequently reverse the movement of the leaf turning arms and return same to normal position.

THOMAS P. ARSNEAU.

Copies of this patent may be obtained for five cents each, by addressing the "Commissioner of Patents, Washington, D. C."
